UNITED STATES PATENT OFFICE

DANIEL M. WINANS, OF BINGHAMTON, NEW YORK, ASSIGNOR TO DANIEL M. WINANS CORPORATION, OF BINGHAMTON, NEW YORK

CAN OPENER

Application filed March 2, 1931. Serial No. 519,324.

My invention relates to can openers and particularly to a can opener which completely and smoothly severs the entire top of the can and which during the severing operation turns down the sharp severed portion around the top of the can so that a smooth surface is left thereon.

One of the principal objects of my invention lies in the provision of a can opener which instead of requiring the operator to hold or steady the can with one hand and cut with and move the can opener with the other hand, grips the can tightly so that it may be easily supported during the cutting operation and upon turning a novel and ingenious cutting mechanism, rotates the can and simultaneously cuts the top thereof.

Another object of my invention is to provide a can opener which enables the cutting of the can top with the supporting hand out of engagement with the can and therefore out of the way of the cutting knife, thus eliminating the likelihood of slippage and resultant cut fingers.

A further object of my invention is to provide a can opener which in operative position also serves as a holder for the can both during and after the cutting operation, whereby the opener is usable as a lifter or handle and eliminates the necessity of the hands touching the can at all. This is particularly useful if the can being opened is hot as in cases where food stuffs are cooked or heated in the can before use.

Another object of my invention lies in the provision of a novel gripping device for the can which serves as a holder, a feeding device, and a guiding means for the cutter.

Other objects and advantages will be apparent as the description proceeds, reference now being had to the figures of the accompanying drawing forming a part of this application wherein like reference numerals indicate like parts.

In the drawing:

Figure 1 is a side view of my improved can opener.

Figure 2 is a view similar to Figure 1 taken from the opposite side, certain parts being broken away and in section for clearness of illustration.

Figure 3 is a detail view partially in section, taken on the line 3-3 of Figure 2, but with the can opener in actual cutting position.

Figure 4 is a detail perspective view illustrating the usefulness of a can opener as a holder or lifting device for the can.

Figure 5 is a detail view illustrating a slight modification of my invention.

In carrying out my invention I provide a pair of lever members 1 and 2, one end of each of which is curved as at 3. The curved ends are offset slightly from the plane of the levers as at 4 and these ends pivoted together as at 5 by any suitable pivot means. Thus there is provided a pair of cooperating levers or clamping jaws, the free ends 6 of which are grasped by the hand of the operator to move the pivoted levers towards and away from each other for a purpose to be described.

A bail 7 is pivoted as at 8 to the lever member 2 and is in the form of a single piece bent back upon itself around the upper lever member 1 whereby the separation of the lever members is limited, and the same are held against lateral displacement. The ends 6 of the levers thus constitute the handles and of course, may be of any desired form or shape or provided with any suitable hand grips as may be desired.

The lever member 2 is provided at a point adjacent the pivoted ends of the levers with a disk or wheel 9, suitably mounted for free rotation on the lever as at 10. The periphery of the disk 9 extends beyond the edge of the lever member 2 as is clear from the figures of the drawing.

Rotatably mounted upon the upper lever

member 1 at a point corresponding with the mounting of the disk 9 on the lever 2, is a toothed wheel 11 adapted to be rotated by means of a crank or finger piece 12, the rotatable parts being suitably journaled as by the sleeve bearing 13 in the lever member 1. Obviously any desired type of rotating means for the toothed wheel 11 may be provided, the finger piece 12 being intended as illustrative only.

The lever member 1 is provided with a lateral extension 14, the upper free end of which is turned over to provide a flange 15 which is cut out centrally as at 16 to receive the reduced end 17 of a knife member 18 secured to the extension 14 in any suitable manner as at 19. Of course, any desired means for securing the knife on the lever 1 may be provided, the form shown being intended as illustrative only.

The knife member 18 is, as shown clearly in Figure 3, offset intermediate its length as at 20 and extends downwardly past the toothed wheel 11 and below the lower edge 25 of the lever member 1. This lower extending end of the knife is pointed as at 21 to provide a piercing means for the top 22 of the can 23. The edges of this pointed end of the knife are, of course, left sharp to provide a cutting means for the top of the can.

The knife 18 provides a bearing as at 24 for the toothed wheel 11 on the opposite side from the lever 1 and of course, confines the toothed wheel 11 in substantial alignment with the rotatable disk 9.

The operation of my invention is as follows:

The operator, first separating the lever members 1 and 2, and consequently the disk 9 and toothed wheel 11, places the device at the upper edge of a can with the pointed end 22 of the knife engaging the edge of the top 22 of the can just inside the bead 25 and with the rotatable disk 9 in engagement with the underside of said bead. This position is shown clearly in Figures 1 and 2. In such position the operator now compresses the handle members 6 of the levers 1 and 2, and of course forces the pointed knife member 50 through the top of the can and downwardly therein directly adjacent the inside surface of the can, until the toothed wheel 11 engages the upper surface of the bead 25. Continued pressure on the handles 6, of course, holds the toothed wheel 11 in tight engagement with the upper surface of the bead 25 and the rotatable disk 9 tightly against the under surface thereof. In this position the cutting end of the knife 18 extends downwardly into the can to a point below the periphery of the rotatable disk 9.

In this position the operator now rotates the finger piece 12 and consequently the toothed wheel 11, the teeth of which bite into the relatively soft metal on the top of the

bead 25 and consequently rotates the can 23, the knife of course, cutting the top 22 during such rotation. A full rotation of the can, results in the complete cutting of the top 22 which may then be removed entirely. It will be clear from Figure 3 that the inner surface of the knife member engages the inner upper edge of the can and bead during the cutting operation, compressing the cut edge thereof between the knife and the bead, the opposing surface of the rotary disk 9, assisting such compression, whereby the cut edge is turned tightly in alongside the inner surface of the can whereby no sharp edges are left when the cutting operation is completed. It will also be noted with reference to Figure 3 that the toothed wheel 11 is offset laterally with respect to the rotary disk 9 a slight amount, sufficient merely to accommodate the thickness of the can 23 between the knife and the disk 9.

From the foregoing it will be obvious that with the can opener in cutting position it acts as a handle or holding device for the can, the can being unable to become detached so long as pressure is maintained upon the handles 6. Therefore, the opener may, as illustrated in Figure 4, be used as a lifting device for the can, thus facilitating pouring the contents out of the can. From the foregoing description it is, of course, obvious that the operator need not necessarily touch the can at all, as the opener may be attached without holding the can and after attachment it securely grips and holds the can. This feature is particularly useful in connection with the opening of cans which are hot or dirty.

In Figure 5 there is shown a slight modification of the invention wherein the position of the rotatable disk and the toothed wheel are reversed from the positions shown in the other figures of the drawing. In Figure 5 the toothed wheel 11a is shown mounted on the lower lever member 2 and the rotatable disk 9a is mounted on the upper lever 1. The operation of the device is identical with that described, the only difference being that in this case the toothed wheel 11a engages and bites into the underside of the bead 25 of the can 23 and the rotatable disk 9a opposes the pressure on the top of the bead. Otherwise the structure and operation of the opener is identical with that just described.

Of course changes may be made in details of construction and arrangement of parts without departing from the spirit and scope of my invention. I do not limit myself to the specific form herein shown and described other than by the appended claims.

I claim:

1. A can opener comprising a pair of pivoted levers provided with a pair of rotatable can gripping means, one of said means having teeth and adapted to engage the upper surface of the bead of a can and acting to

turn the can when rotated, the other of said means being adapted to engage the under surface of said bead in opposing relation to said first means and in substantial alignment therewith, and a knife carried by one of said levers and independent of said gripping means operable to cut the top of said can when turned.

2. A can opener comprising a pair of levers pivoted together at one end, rotatable can gripping means on said levers intermediate their ends and in substantial alignment said means comprising a toothed wheel adapted to engage the upper surface of the bead of a can and a second wheel adapted to engage the underside of said bead in opposing relation to said toothed wheel, said means coacting to turn the can when rotated in gripping position, and a knife independent of said gripping means in top-cutting position during such turning, said knife being carried by one of said levers and extending to a position alongside said gripping means but inside the can.

25 3. A can opener comprising a pair of levers pivoted together at one end, rotatable can gripping means on said levers intermediate their ends and in substantial alignment, said means coacting to turn the can when rotated in gripping position, and a knife carried by one of said levers and independent of said gripping means in top cutting position during such turning for cutting the said top inside of said bead, one of said gripping means being toothed and adapted to bite into the upper surface of the bead of the can upon rotation, for turning the can.

4. A can opener comprising a pair of pivoted parallel levers each provided with a rotatable can gripping wheel mounted in substantially opposing relation intermediate the ends of said levers and one of said wheels being toothed for biting into the top surface of the bead of the can when in gripping position, means for rotating said toothed wheel to turn the can and a knife independent of said gripping means and carried by one of said levers adapted to cut the can top inside the bead as the can is turned.

50 5. A can opener comprising a pair of pivoted parallel levers each provided with a rotatable can gripping wheel mounted in substantially opposing relation intermediate the ends of said levers and one of said wheels being toothed for biting in the top surface of the bead of the can when in gripping position, means for rotating said toothed wheel to turn the can and a knife independent of said gripping means and carried by one of said levers adapted to cut the can top as the can is turned, said knife extending into the can beyond the peripheries of both of said wheels in cutting position.

65 6. A can opener comprising a pair of levers pivoted together at one end, rotatable

can gripping means on said levers intermediate their ends and in parallel alignment with each other in operative position and offset from each other an amount substantially the thickness of the can material, said means 70 coacting to turn the can when rotated in gripping position, and a knife carried by one of said levers and independent of said gripping means in top cutting position during such turning, one of said gripping means being 75 toothed and adapted to bite into the upper surface of the bead of the can upon rotation, for turning the can.

In testimony whereof, I affix my signature.
